Advertisement by Wilson Corporation issued Jul. 1978, in "Golf Digest", for REFLEX putter head.

Primary Examiner—Melvin B. Feifer
Attorney, Agent, or Firm—Poms, Smith, Lande & Rose

[57] CLAIM

The ornamental design for a golf putter head, as shown and described.

DESCRIPTION

FIG. 1 is a top view of a golf putter head showing my new design;

FIG. 2 is a front view of the golf putter head of FIG. 1; FIG. 3 is a left side view of the golf putter head of FIG. 1;

FIG. 4 is a right side view of the gold putter head of FIG. 1;

FIG. 5 is a back view of the golf putter head of FIG. 1; and

FIG. 6 is a bottom view of the golf putter head of FIG. 1.

The broken line showing of a shaft portion in FIGS. 2 and 5 is for illustrative purposes only.
